UNITED STATES PATENT OFFICE.

GUIDO SEMENZA, OF MILAN, ITALY.

ELECTRIC INSULATOR.

1,333,640.

Specification of Letters Patent. Patented Mar. 16, 1920.

Application filed January 23, 1918. Serial No. 213,316.

To all whom it may concern:

Be it known that I, GUIDO SEMENZA, subject of the King of Italy, resident at Milan, in the Kingdom of Italy, No. 10 Via Santa 5 Ravegonda, have invented new and useful Improvements in Electric Insulators, of which the following is a specification.

This invention relates to insulators of the suspension type in which the insulating 10 member of porcelain, glass or any other insulating material, carries on its upper part a metal cap, fixed to it in some appropriate way more generally by means of cement.

The principal object of the invention is to 15 provide a new and improved construction, combination and arrangement of parts by which any stresses due to different rates of expansion or contraction of the materials used may be avoided or so directed that they 20 will not cause the breakage of the insulating member.

In effecting this object, the arrangement adopted and hereinafter described is of such 25 a character as not to require any cement or other matter to be employed in order to fix the cap to the insulating element, and a space is provided to allow expansion and contractions of the different parts employed without generating dangerous stresses.

30 The invention has also the object of rendering difficult the falling out of the insulating member from the cap when for any reason it fails owing to mechanical actions or an electric flash over, or when it becomes 35 punctured.

In the accompanying drawings, Figure 1 is a view partly in section and partly in elevation of an insulator having a conical shaped head, carried by a metal cap, made 40 to properly fit it, Fig. 2 is a sectional view taken on the line A B. The construction and shape of the cap may be varied as required: in the figures one example is given to show the principle of the invention.

45 In the figures; 1 is an insulator of the suspension type the particular form of which has no importance provided that the head be made in the form of an inverted cone; care should be taken that the portion 7—8 of the 50 surface of the insulator should be as nearly as possible accurately conical.

The cap is made of three parts: a round top piece or disk 9 and two semi-annular side pieces 5. The three parts of the cap 55 may be of any kind of suitable metal such as cast-iron or steel, and the top piece or part

is spaced from the top of the insulator, so as to permit expansion to take place to different extents.

It will be noted that the two side pieces 5 60 form in the interior a conical surface which must have the same inclination as the conical outer surface 7—8 of the insulator 1.

In order to obtain a continuous contact between the cap and the insulator the inner 65 conical surface of the cap is faced with a layer 6 of very soft metal which can be, if necessary, turned out or adjusted by any other suitable means.

This soft metal may be cast on the two 70 side pieces 5 in which two dovetail grooves (12) as shown in section in Fig. 1 are formed. It may also be pressed in place by any known mechanical process.

In the place of this coating of soft metal 75 a layer of any other suitable soft substance can be used.

The three parts of the cap are kept together by bolts 11.

10 is a threaded hole for fastening the upper eyebolt. The inner rod 4 may be fixed 80 to the insulator by means of cement or by a layer of electrolytically deposited material in which the rod is screwed, or by any other appropriate means.

It can be easily understood that the insulator when suspended will force its conical surface against the soft metal or other interposed material and will tend to contact 85 squarely with it all over.

As a result of this fact it will be seen that 90 all mechanical strain will be distributed over a large surface, and the resulting stresses imposed upon the porcelain will be only compression.

Owing to the conical shape of the surfaces 95 in contact the insulator is free to move up and down in the cap, and the differences of expansion between the porcelain and the metal cannot produce any overstrain but will 100 result in a slight relative motion.

As to the danger of the insulator falling 105 out of the cap when the insulator breaks for any reason, it will be seen that, owing to the conical shape of the head the liability of this happening is very much reduced.

Having now described my invention and how the same is to be carried out, what I claim as my invention, is:

1. A suspension insulator, comprising an 110 insulating element having an outer conical surface; and a suspension cap consisting of a

top member in the form of a disk, and a pair of companion, semi-conical side members connected to said top member and having their inner surfaces uniting to provide a single, continuous conical surface which conformably fits against and movably rests upon the first-named conical surface throughout its entire extent, both conical surfaces having their apices directed downward; said top member having its lower surface spaced from the top surface of said insulating element when said conical surfaces are in such engagement, to provide a clearance space which allows for the expansion of said cap and said insulating element to different extents.

2. A suspension insulator, comprising an insulating element of vitreous material having an outer conical surface; a metal suspension cap consisting of a top member in the form of a disk, and a pair of companion

side members connected to said top member and having their inner surfaces uniting to provide a single continuous conical surface which has the same inclination as the first-named conical surface, both conical surfaces having their vertices directed downward; and a facing of soft metal interposed between said conical surfaces and secured to one of them, the other conical surface fitting conformably against said facing throughout its entire extent and movably resting upon the same; said top member having its lower surface spaced from the top surface of said insulating element when said conical surfaces are in such engagement, to provide a clearance space which allows for the expansion of said cap and said insulating element to different extents.

In testimony whereof I affix my signature. 40

GUIDO SEMENZA.
